UNITED STATES PATENT OFFICE.

WILLIAM HENRY ELFRETH, OF WESTTOWN, AND GUSTAV B. WEISS, OF PHILADELPHIA, PENNSYLVANIA.

DESIGN FOR A SLED.

Application filed January 20, 1927. Serial No. 20,447. Term of patent 14 years.

To all whom it may concern:

Be it known that we, WILLIAM HENRY ELFRETH and GUSTAV B. WEISS, citizens of the United States, residing, respectively, at Westtown, in the county of Chester and State of Pennsylvania, and at Philadelphia, in the county of Philadelphia and State of Pennsylvania, have invented a new, original, and ornamental Design for Sleds, of which the following is a specification, reference being had to the accompanying drawing, forming a part thereof.

We claim;

The ornamental design for a sled, substantially as shown.

WILLIAM HENRY ELFRETH.
GUSTAV B. WEISS.
